CLAIM

The ornamental design for a video conferencing codec unit, as shown and described.

DESCRIPTION

FIG. 1 is a perspective view of a video conferencing codec unit, showing our new design;

FIG. 2 is a front elevational view of thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is another perspective view of the video conferencing codec unit shown in an alternate configuration;

FIG. 9 is a front view thereof; and,

FIG. 10 is a left side elevational view thereof.

The broken lines depicted in FIGS. 1-10 depict portions of the video conferencing codec unit that form no part of the claimed design.

The oblique shade lines shown on the front of the unit in FIGS. 1-2 and 8 depict a reflective surface.

1 Claim, 7 Drawing Sheets(56)
